UNITED STATES PATENT OFFICE

1,951,934

DUPLICATOR

Shinjiro Horii, Tokyo, Japan

Application December 5, 1932, Serial No. 645,831
In Japan January 22, 1932

4 Claims. (Cl. 101—126)

This invention relates to a duplicator, more particularly to a flat duplicator of the type in which a stencil stretching frame is swingably connected at one end to a bed of the duplicator.

5 One object of the invention is to provide a duplicator of this type in which the stencil stretching frame can be readily removed from the bed without handling any part for disconnecting the same.

10 Another object of the invention is to provide a duplicator of the simplest construction in which the position of the trunnions on the stencil stretching frame is automatically adjusted in accordance with the thickness of the pile of papers placed on the bed when the stencil stretching

15 frame is lowered into a printing position.

A further object of the invention is to provide a duplicator in which the stencil stretching frame is normally tending to swing upwardly by the action of the springs, whereas said springs are adapted to be held in an ineffective position so that the tendency of the stencil stretching frame of being automatically sprung up can be removed when it is so desired.

20 With the above-mentioned objects in view, the duplicator according to the invention comprises a bed, a stencil stretching frame having trunnions and extension arms extending rearwardly, brackets secured to said bed and each having a bearing slot open at the upper end being adapted to receive said trunnions on the stencil stretching frame, rocking arms abutting against said extension arms on the stencil stretching frame, and springs tending to turn said rocking arms forwardly.

25 In the accompanying drawings,

Figure 1 is a plan view of a duplicator according to this invention;

Figure 2 is an enlarged side view partly in section of the rear portion of the duplicator shown in Figure 1;

Figure 3 is a sectional end view thereof;

Figure 4 is a side view similar to Figure 2, but with the spring in its ineffective position;

Figure 5 is a side view partly in section of the rear portion of a modified construction according to this invention; and

Figure 6 is a sectional end view thereof.

Referring to the drawings, 1 is a bed of the duplicator and is provided with brackets 2 secured one on each side at the rear end thereof. Each of said brackets 2 has a vertical open slot 3. 4 is a stencil stretching frame and is provided with extension arms 5 secured thereto on both sides. Said extension arms 5 carry trunnions 6

which are adapted to be slidably mounted in the said bearing slots 3 in the brackets 2, so that the stencil stretching frame 4 is swingably connected to the bed 1.

At each side of the bed 1, pivoted at 7 to the bracket 2 is a rocking arm 8, of which upper end co-operates with the extension arm 5 of the stencil stretching frame 4. Preferably said rocking arm 8 carries a roller 9 at its upper end, and is normally pressed against the extension arm 5 by means of a spring 10 which tends to pull the arm 8 forwardly. Means is provided for releasing the tension of the spring 10. For this purpose, in the bracket 2 is provided a slot 11 having dent portions 12 and 13 at its ends, and therein is inserted a pin 14 to which the forward end of the spring 10 is connected. Preferably a knob 15 is secured to the outer end of the pin 14. When the pin 14 is moved forwardly by means of the knob 15 and is engaged by the forward dent portion 11, the spring 10 is maintained under tension, so that the spring 10 is strong enough to act upon the extension arm 5 through the arm 8 to springly lift the stencil frame 4, as shown in chain lines in Figure 2. When the pin 14 is removed from the dent portion 11, it returns to the rear dent portion 13, as shown in Figure 4, and the spring 10 will become practically ineffective, so that the stencil frame 4 is maintained in its lowered position.

For the sake of simplicity the arrangement of the parts has been described with reference to only one side of the duplicator, but it is to be understood that the device on the opposite side is similarly constructed.

When the stencil stretching frame 4 is swung upwardly the extension arm 5 thereof will become free from the rocking arm 8. Thus, it will be seen, the stencil stretching frame 4 can be readily disconnected by merely lifting it vertically without necessitating handling of any part for disconnection.

In the duplicator described above, as the trunnion 6 of the stencil stretching frame 4 is adapted to slide along the vertical slot 3 and as the upper end of the arm 8 is adapted to abut against the outer edge of the extension arm 5 at different points according to different positions of the trunnion 6 in the slot 3, it will be seen that when the stencil stretching frame 4 is lowered to a printing position it will always assume automatically adjusted position according to the thickness of the pile of papers placed on the bed 1.

A slightly modified construction is shown in Figures 5 and 6. In this modification, the open

slot 3' is formed in an inner bracket 2' secured to the bed 1', and on an outer bracket 22 a bell crank lever 8' is rockably mounted at 7'. The lower arm of said bell crank lever 8' carries a 5 roller 9' and is pressed against the upper or outer edge of the extension arm 5' on the stencil frame 4' by means of the spring 10', of which one end is connected to the upper arm of the bell crank lever 8'. The other end of the spring 10' 10 is connected to a bar 14' which is pivoted at its rear end to the inner bracket 2', and having at its forward end a key 15'. To the outer bracket 22 is secured a spring bar 23 on which are formed 15 detent teeth 12' and 13', and the lower free end thereof is provided with an extension 24 lead out of the bracket through a hole. The bar 14' is normally held engaged by the lower detent tooth 11' so that the spring 10' is maintained under tension. For releasing the tension of said 20 spring 10' the extension 24 of the spring bar 23 is pushed inwardly, whereby the bar 14' is released from the lower detent tooth 12' and returns to the uppermost position. When the spring bar 23 is engaged by the upper detent tooth 13', the 25 tension of the spring 10' is partly released so that a slower swing motion of the stencil stretching frame 4' can be attained. When it is desired to secure full tension of the spring 10', the key 15' is merely pressed down to be engaged by the 30 lower detent tooth 12'. The function of the parts shown in Figures 5 and 6 is substantially similar to that of the construction shown in Figures 1 to 4, and it will be obvious without describing any further.

55 What I claim is:—

1. A flat duplicator comprising a bed, a stencil

stretching frame having trunnions and extension arms extending downwardly and rearwardly beyond said trunnions, brackets secured to said bed and each having a bearing slot open at the upper end being adapted to receive said trunnions on the stencil stretching frame, and spring biased rocking arms abutting against said extension arms on the stencil stretching frame so as to normally maintain said trunnions pressed downwardly in said bearing slot and yet to tend to turn said stencil stretching frame upwardly about said trunnions. 80

2. A flat duplicator comprising a bed, a stencil stretching frame having trunnions and extension arms extending rearwardly, brackets secured to said bed and each having a bearing slot open at the upper end being adapted to receive said trunnions on the stencil stretching frame, rocking arms abutting against said extension arms on the stencil stretching frame, springs tending to turn 85 said rocking arms forwardly, and means for holding said springs in ineffective position. 90

3. A flat duplicator as set forth in claim 1, wherein each of the rocking arms is provided with a roller which cooperates with the extension arm on the stencil stretching frame. 100

4. A flat duplicator as set forth in claim 2, wherein each spring is connected at its one end to the rocking arm and is connected at the other end to a pin, which pin being inserted into a 105 slot formed in the bracket and having a dent portion at its forward end, the arrangement being such that by the engagement of said pin with the forward dent portion of the slot the spring is maintained under tension. 110
